US0D1068477S

(12) United States Design Patent (10) Patent No.: US D1,068,477 S
(45) Date of Patent: * Apr. 1, 2025

(54) BOTTLE CAP WITH SURFACE ORNAMENTATION

(71) Applicant: Express Scripts Strategic Development, Inc., St. Louis, MO (US)

(72) Inventors: Mark G. Bini, O'Fallon, MO (US); Nicholas D. Main, St. Louis, MO (US); Sara A. Raj, St. Louis, MO (US); Sarah E. Ham, Bloomington, IN (US)

(73) Assignee: Express Scripts Strategic Development, Inc., St. Louis, MO (US)

() Term: 15 Years

(21) Appl. No.: 29/936,491

(22) Filed: Apr. 9, 2024

Related U.S. Application Data

(62) Division of application No. 29/881,778, filed on Jan. 6, 2023, now Pat. No. Des. 1,032,362, which is a division of application No. 29/747,902, filed on Aug. 26, 2020, now Pat. No. Des. 974,911, which is a division of application No. 29/642,284, filed on Mar. 28, 2018, now Pat. No. Des. 897,844.

(57) CLAIM

The ornamental design for a bottle cap with surface ornamentation as shown and described.

DESCRIPTION

FIG. 1 is a top view of a bottle cap with surface ornamentation showing the new design; and,

FIG. 2 is a front view thereof, the rear, right side, and left side views being identical thereto.

The broken lines depict portions of the bottle cap with surface ornamentation that form no part of the claimed design.

1 Claim, 2 Drawing Sheets
